UNITED STATES PATENT OFFICE.

THOMAS DOCKRAY, OF BUFFALO, NEW YORK.

DESIGN FOR AN AUTOMOBILE EMBLEM PLATE.

Application filed September 8, 1925. Serial No. 14,724. Term of patent 3½ years.

To all whom it may concern:

Be it known that I, THOMAS DOCKRAY, a subject of the King of Great Britain, residing at Buffalo, in the county of Erie and State of New York, have invented a new, original, and ornamental Design for Automobile Emblem Plate, of which the following is a specification, reference being had to the accompanying drawing, forming a part thereof.

Figure 1 is a front elevational view of my automobile emblem plate, showing my new design, and Figure 2 is a perspective view thereof showing the rear face.

I claim:

The ornamental design for an automobile emblem plate, as shown.

THOMAS DOCKRAY.
